UNITED STATES PATENT OFFICE.

FREDERICK C. BROCKER, OF OAKLAND, CALIFORNIA, ASSIGNOR OF ONE-HALF TO
SYLVANUS C. FARNHAM, OF OAKLAND, CALIFORNIA.

NONGLARE DEVICE FOR HEADLIGHTS.

Application filed June 30, 1921. Serial No. 481,463.

To all whom it may concern:

Be it known that I, FREDERICK C. BROCKER, a citizen of the United States, and a resident of Oakland, county of Alameda, and State of California, have invented a new and useful Non-Glare Device for Headlights, of which the following is a specification.

My invention relates to a device for reducing the objectionable glare usually characteristic of headlights of comparatively high power.

An object of the invention is to provide a non-glare device in which all of the various parts thereof are formed into an independent unit or structure which may be substituted bodily for the usual lens of the headlight.

Another object of the invention is to provide a device of the character described which is simple and inexpensive in construction.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claim.

Referring to said drawings:

Figure 1 is a vertical section through the device of my invention.

Figure 2 is a rear view of the device.

Figure 3 is a vertical sectional view of an ordinary headlight equipped with the non-glare device of my invention.

The device as shown in the present embodiment of the invention is particularly adapted for use in connection with the usual type of headlight, which as shown in Figure 3 comprises a housing 4 in which a parabolic reflector 6 is disposed, the source of light being in the form of an incandescent lamp 7 whose filament 8 lies at the focal point of the reflector.

Engaged within the annular groove formed between the ring 10 and housing 4, which heretofore has ordinarily been engaged by the headlight lens, is a circular disk 12 which carries the associated parts of the non-glare device substantially inde-

pendent of the headlight members. The disk is formed of an opaque or translucent material—preferably the former—and is provided in its upper portion with a concentric segmental opening 13 whose lower edge 14 is preferably horizontally disposed and forms the chord of the segment. The lower edge 14 of the opening lies above the center of the disk an amount sufficient to render the source of light invisible from the outside of the headlight when viewed from the front at any angle on a horizontal line. In this manner the dazzling rays emitted directly from the light source will ordinarily not be seen. Secured to the lower portion of the inner side of the disk 12 is a secondary reflector 16 which is arranged to underlie the source of light so that the rays emanating from the latter are caused to be reflected from the member 16 back against the main reflector 6 and thence through the opening 13. The inner side of the disk between the edge 14 of the opening and the reflector 16, is provided with a high light-reflecting surface 17 so that the rays striking it may be reflected against the reflector 6 and ultimately discharged through the opening. It will thus be noted that the light discharged through the disk opening 13 is the result of the combined effect of the rays reflected against the reflector 6 directly from the light source and the rays reflected against said reflector from the reflector 16 and the reflecting surface 17. In this manner a highly concentrated powerful beam of light may be projected over the area in front of the headlight without exposing the source of light thereto. By referring to Figure 2 it will be seen that the reflector 16 is substantially segmental in form, the curved edge being adapted to fit more or less snugly against the parabolic reflector 6 from one side of the latter to the other. In this manner practically all of the downwardly projected rays will be directly intercepted by reflector 16 and none will be pocketed in the bottom of the headlight.

The opening 13 is preferably covered by a transparent medium such as the segmental shaped glass 18 which as here shown is supported in a bracket 19 attached to the disk. When the complete device is positioned in the headlight the curved edge 21 of the glass preferably engages between the ring 10 and the headlight casing similar to the disk, and

a piece of felt 22 or the like is preferably interposed between the edge 21 and the disk, thus enabling the glass to be held in rigid position. A pad 23 is also adapted to be interposed between the disk and casing where they are unengaged by the glass.

The device is preferably provided with a visor 24 which extends outwardly from the upper edge of the opening 13 and acts to 10 deflect the discharging rays downwardly.

It will now be understood that a very effective non-glare device is provided which may be readily placed on headlights of present day construction without necessitating 15 any change therein with the exception of the substitution of the lens.

I claim:

A non-glare device for headlights having a substantially parabolic reflector and

a source of light at the focal point thereof, 20 a member arranged to serve as the sole closure for the opening of the headlight receptacle and comprising a circular disk of opaque material and provided in one portion with a segmental opening of less than half 25 the area of the disk, a glass supported by said disk and arranged to cover said opening, and an obliquely extending secondary reflector fixed to said disk and having a curved edge adapted to fit against the parabolic reflector of the headlight and positioned to reflect the rays from said light source against the primary reflector.

In testimony whereof, I have hereunto set my hand at Oakland, California, this 25 35 day of June, 1921.

FREDERICK C. BROCKER.
